US00D810726S

(12) United States Design Patent (10) Patent No.: US D810,726 S
(45) Date of Patent: * Feb. 20, 2018

(54) PORTABLE ELECTRONIC DEVICE

(71) Applicant: HTC Corporation, Taoyuan (TW)

(72) Inventors: Chin-Wei Chou, Taoyuan (TW);
Yi-Shen Wang, Taoyuan (TW);
Chien-Hsin Huang, Taoyuan (TW);
Meng-Sheng Chiang, Taoyuan (TW);
Lee-Wei Chen, Taoyuan (TW);
Yien-chun Kuo, Taoyuan (TW);
Hung-Yu Chen, Taoyuan (TW)

(73) Assignee: HTC Corporation, Taoyuan (TW)

() Term: 15 Years

(21) Appl. No.: 29/573,395

(22) Filed: Aug. 5, 2016

(51) LOC (11) Cl. 14-03

(52) U.S. Cl.

USPC D14/248

(58) Field of Classification Search

USPC ..... D14/138 G, 138 AD, 341, 138 R, 496,
D14/203.1, 203.3, 203.5, 203.7, 248;
455/575.1, 556.2; D21/517, 329;
361/679.3, 679.56

CPC . G06F 1/1626; H04M 1/0266; H04M 1/0264;
H04M 1/0202

See application file for complete search history.

(57) CLAIM

The ornamental design for a portable electronic device, as shown and described.

DESCRIPTION

FIG. 1 is a perspective view of a first embodiment of a portable electronic device in accordance with our new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a perspective view of a second embodiment of a portable electronic device in accordance with our new design;

FIG. 10 is another perspective view thereof;

FIG. 11 is a front view thereof;

FIG. 12 is a rear view thereof;

FIG. 13 is a left side view thereof;

FIG. 14 is a right side view thereof;

FIG. 15 is a top view thereof; and,

FIG. 16 is a bottom view thereof.

The portions of the portable electronic device shown in broken lines form no part of the claimed design.

1 Claim, 12 Drawing Sheets
